STOKER

Joseph R. Robinson, Pittsburgh, Pa.

Application December 17, 1937, Serial No. 180,287

8 Claims. (Cl. 110—45)

My invention is an improvement in stokers, of the kind wherein a mass of fuel, as coal, is successively progressed from a supply reservoir or container to and upwardly through a burner 5 grate or the like for combustion, usually in connection with a suitable air supply. Ordinarily, such burner or fuel supply member is of circular ring form, the annular wall surrounding the fuel supply middle or bowl portion and having inwardly directed air supply ports, of various constructions.

In the combustion of coal in such stokers, the volatile gases are distilled away and burned and the coal tends to become coke upon emerging 15 upwardly into the combustion zone. In such progress and combustion, the mass of upwardly moving coal, due to preliminary coking, assumes a so-called "tree" form, and must be broken down or separated at intervals for the best results in final and complete combustion and for securing the full heating value of the fuel. Various means have been utilized for thus separating or breaking down the partially coked fuel, such as by active hand or mechanical stoking, etc.

My invention provides means whereby the upwardly moving mass of partially coked coal is automatically separated as it emerges through the fire bowl or retort of the burner. In such progress the mass of fuel is divided into sectional portions which fall outwardly in more or less separated condition, with the resulting advantage of final thorough and complete combustion. Ordinarily, any resulting clinker formation may be readily removed from time to time 30 over the usual supporting grate bottom or floor and outwardly through the usual door of the furnace.

The invention is illustrated in the accompanying drawing, in which:

Fig. 1 shows in elevation and section the invention as applied to the burner of a hot water boiler;

Fig. 2 is an enlarged plan view of one form of the supplemental stoker distributor located 45 across the top of the burner;

Fig. 3 is a vertical section on the line III—III of Fig. 2;

Fig. 4 is a transverse sectional view on the line IV—IV of Fig. 2;

Fig. 5 is a plan view like Fig. 2 showing a modified construction;

Fig. 6 is a sectional view on the line VI—VI of Fig. 5;

Fig. 7 is a similar plan view showing a further 55 modification, utilizing a single cross bar;

Fig. 8 is a cross section thereof on the line VIII—VIII of Fig. 7;

Figs. 9 and 10 show further modifications in plan view.

Referring to the drawing, A represents the outer portion of one form of standard fuel supply construction provided with a coal hopper or chamber, an air blower, and a feeding coal propeller 2 for advancing the fuel inwardly and upwardly through the chamber B of the burner, as shown in Fig. 3.

Such chamber, in the form shown, is circular in cross section, flaring upwardly toward the open top and of tuyère type, provided with air inlet openings 3 communicating with a surrounding air supply chamber 4 between the inner and outer walls 5 and 6 of the burner. Such chamber is in communication by opening 7 with the hollow interior 8 communicating backwardly with the blower of the equipment, not necessarily described.

In such construction, as in others now in use, fuel in the form of sized coal is fed by the worm 2 into the bottom of chamber B and upwardly therethrough to and outwardly from the top into the zone of combustion of the furnace, in connection with the air supply. However, because of the intense heat, the upper portion of the burner is subject to partial destruction and requires replacement, either entire, or when in sectional form, of one or more sections.

The object of the invention is to provide means located at the emergence top of the burner for separating the mass of fuel or the so-called "tree" into plural sections for upward and outward dispersion, for better combustion, and avoidance of hand or mechanical stoking. Also to provide such means with fluid circulation cavities for protection against excess heat destruction and also for avoiding such in the burner itself.

Such means comprise one or more transverse bars or separating members as in the different constructions shown.

Thus in Fig. 7 I may utilize a transverse bar 9 extending across the middle of the top of chamber B and secured to its annular rim in any suitable manner, as by flanges 10 or otherwise.

In cross section such separating bar is preferably tapered downwardly and inwardly in wedge formation as indicated at 11, whereby to provide an initial dividing edge 12 against which the upwardly moving mass of fuel engages, separating it into two opposite sections. As the fuel feeding operation progresses such sections will become distributed upwardly and outwardly in more or

less broken-up form, avoiding the objection of the "tree" formation, and dispersing the fuel outwardly for better and more complete combustion as desired.

5 The bar 9 is preferably hollow as shown at 13 for circulation of cooling water therethrough by an inlet supply pipe 14 and an outlet pipe 15, at opposite ends.

In the construction shown in Fig. 2, I utilize 10 double cross bars 9a arranged in X form, whereby to provide alternating openings or spaces 16, through which the upwardly moving separated sections of fuel may emerge. By such construction the separation is rendered more complete 15 and of reduced mass size, ensuring multiple division of the main body.

In such construction the opposite pairs of bars 9a are connected by annular hollow segmental sections 17 which communicate with the hollow 20 interior of the several cross bar sections, thus providing complete water circulation passages from the inlet pipe connection 14a to the outlet pipe connection 15a. Cross bars or arms 9a are of the same general wedge form in cross section 25 as indicated in Fig. 8, and as thus constructed will operate for multiple division of the mass of fuel, together with the water cooling function.

As shown in Fig. 1 the water circulation by 30 pipes 14 and 15 is in combination with the main annular water chamber C of a boiler, when used therewith. Otherwise the pipes may be connected in any suitable manner with a water supply and exhaust system of any suitable or varied construction.

35 The construction of Figs. 5 and 6 is of the same general form as to the cross bar arrangement above described, but is provided with a depending annular hollow section 11a adapted to embrace the main burner around its outer wall 6, as indicated in Fig. 6. Such depending skirt or double wall is in continuous water circulation with the upper cross separation portion and is provided with corresponding supply and exhaust pipes 14 and 15.

45 By such arrangement the entire body portion of the main burner may be protected against excess heat and resulting deterioration, the construction being preferably in one continuous form adapted to fit thereon and thereover.

50 Any suitable arrangement of the supply and outlet connections 14 and 15 may be utilized. In ordinary installation such are preferably located either bodily through or just below the surface of the main hearth 18, in either a water heating or ordinary furnace construction, as will be readily understood. The cooling fluid, as water or air, is of course controlled by suitable valve regulation in the usual way.

60 A further modification is illustrated in Fig. 9 in which the single cross bar form 9 of Fig. 7 is provided at its middle portion with oppositely extending comparatively short dividing projections or branches 19, also cored for water circulation as indicated in dotted lines.

65 Such middle extensions are of variable or suitable length and provide additional dividing members tending to effect lateral separation of the mass of fuel. In such form a greater or more complete plural division of the mass will be effected by a single cross bar provided with such middle opposite extensions.

70 Fig. 10 illustrates a further modified form in which two diverging arms 9b connect with a 75 segmental rim 17b and with an oppositely dis-

posed arm 9c providing three diverging outlet spaces 16b.

The different forms of my improved stationary stoker may be readily made of cast metal, as iron or other metals or alloys thereof, for durability. While these may conveniently be separately attached to the burner, it is obvious that they may also be cast integrally therewith, as preferred.

Also that the cross arms may be changed in form, arrangement or cross section as desired to suit varying conditions of use or combination with different types of retort burners.

The construction and manner of operation of the invention will be readily understood and appreciated from the foregoing description in connection with the different forms illustrated.

It effectually accomplishes the breaking up of the partly coked mass of fuel, and avoids the necessity of hand separation or stoking, with resulting better combustion and reduction of clinker.

Any such clinker may be removed from time to time in the usual manner. It will be understood also that the propelling force of the feeding worm 2, together with the inner flaring surface of the wall of chamber B, positively forces the fuel upwardly against the dividing cross bar or bars.

It will be understood also that the invention may be variously changed or modified in detail construction for application and use on different forms of burners, but that all such changes, which may be made by the skilled mechanic, are to be understood as within the scope of the following claims.

What I claim is:

1. In combination with the unitary air supply combustion fire bowl of a fuel supply member, an upper separately attached transverse fuel separator consisting of a plurality of integral hollow downwardly and inwardly tapering cross bars extending over the bowl above its air supply providing separated fuel emergence openings and having fluid circulation supply and outlet connections and removably laid over the rim of the fire bowl above its air supply.

2. In combination with a lower air supply combustion fire bowl of a fuel supply member, an uppermost separable transverse fuel separator consisting of a plurality of hollow cross bars extending over the top of the bowl providing separated fuel emergence openings between the cross bars and the inner bowl rim and having an annular hollow rim and a depending hollow wall communicating with the hollow bars and with fluid supply and outlet connections and removably laid over and around the fire bowl.

3. Fuel separating means for the unitary fire bowl of a burner as described having air supply openings through its sides consisting of a separable unitary transverse hollow bar adapted to be located across and secured to the top thereof having a wedge shaped fuel separating bottom terminating at the top of the fire bowl and water inlet and outlet connections at opposite ends of the bar.

4. Fuel separating means for the unitary fire bowl of a burner as described consisting of a plurality of centrally connected integral radial hollow arms having wedging bottom portions terminating at the top of the fire bowl and intervening fuel clearance spaces, and endmost circulation portions communicating with the hollow

arms, with means for securing same to the fire bowl.

5. Fuel separating means for the unitary fire bowl of a burner as described consisting of a plurality of centrally connected spaced apart radial hollow arms having hollow downwardly tapering wedging bottoms terminating above the fire bowl and in fluid circulation connection with a depending integral surrounding hollow wall provided with fluid supply and outlet connections.

6. In combination with a combustion fire bowl having a lower fuel supply connection and an outer air casing with air supply openings through the bowl below its upper rim, an independent fuel separator consisting of a hollow annular rim removably secured to the rim of the bowl and provided with inner fuel clearance openings and transverse hollow cross bars in fluid circulation with the separator rim and having flat upper faces and tapering wedge lower faces, said annu-

lar rim and cross bars being of substantially uniform depth.

7. In combination with the unitary air supply combustion fire bowl of a fuel supply member, an upper transverse hollow fuel separating bar for circulation therethrough of a cooling medium removably secured to the rim of the fire bowl above its air supply and having a lower downwardly and inwardly tapering portion, with fuel emergence openings at opposite sides of the bar. 10

8. In combination with the unitary air supply combustion fire bowl of a fuel supply member, an upper transverse hollow fuel separating bar for circulation therethrough of a cooling medium removably secured to the rim of the fire bowl above its air supply and having a lower downwardly and inwardly tapering portion and middle oppositely extending tapered dividing projections, with fuel emergence openings at opposite sides of the bar. 15

JOSEPH R. ROBINSON. 20
